CEMENTING OF WELLS

James L. Rike, New Orleans, La., assignor, by mesne assignments, to Jersey Production Research Company, Tulsa, Okla., a corporation of Delaware

Filed May 7, 1962, Ser. No. 192,866

9 Claims. (Cl. 166—26)

The present invention is directed to a method for cementing wells. More particularly, the invention is directed to cementing a well having a plurality of parallel pipe strings arranged therein. In its more specific aspects, the invention is concerned with method and apparatus for cementing wells such as those producing hydrocarbons such as oil and gas.

This application is a continuation-in-part of Serial No. 846,969, entitled "Cementing of Oil Wells," filed October 16, 1959, for James L. Rike.

The present invention may be briefly described as a method for cementing a plurality of side-by-side parallel pipe strings which are fluidly interconnected. One of the pipe strings allows passage of fluids out of its lower end and another of the pipe strings allows passage of fluids through its wall at a selected point. In the practice of the present invention, a cementitious material such as Portland cement and the like is flowed down one of the pipe strings and out the end thereof to fill the annulus between the pipe strings and the wall of the well bore to a predetermined level below the selected point while maintaining another of those pipe strings free of cementitious material. Cementitious material is then flowed down the other of the pipe strings and into the annulus above the first flowed cementitious material while maintaining the one pipe string free of cementitious material. Thereafter, a displacing fluid is flowed down the one pipe string to displace cementitious material from the other pipe string whereby the pipe strings are cemented in the well bore.

In the cementing of strings of pipe such as casing in oil and gas wells, it is often desirable or necessary to cement by stages by cementing through an upper port in the pipe string after the first stage cement around the lower portion of the string has set. In usual practice this is accomplished by means of a special tool run to the desired point such that by releasing to the fluid stream a drillable plug-type opening device, fluid passage may be stopped below the tool and a port opened to the outer portion of the casing string. A follower plug is then used behind the cement to indicate at the surface when the cement is properly in place. This procedure is unsatisfactory in that it requires the subsequent drilling of the cement and sealing plugs used to perform the necessary closing and opening functions of the tool.

In making tubingless completions whereby a plurality of side-by-side parallel pipe strings are arranged in a hole, the usual string of pipe is cemented inside the well bore to become a permanent casing of a well. In these situations it may even be desirable to have cement covering the annulus between the wall of the well and the casing to a point higher than it is feasible to circulate from the bottom of the well. For example, in many cases it may be desirable to have a cement sheath completely around the pipe up to the surface pipe or to the surface of the ground. In the practice of the present invention, method and apparatus are provided for stage cementing such wells when two or more side-by-side pipe strings are used, which does not require drilling out before perforation and final completion of the wells.

The present invention will be further illustrated by reference to the drawing in which:

FIGS. 1 to 3 illustrate apparatus in section for per-

2

forming a stepwise mode of practicing the present invention in dual pipe strings;

FIG. 4 is a schematic sectional view of apparatus for performing the invention in quadruple strings of pipes;

FIG. 5 is a detailed view in partial section of the check valves of FIGS. 1 to 4; and

FIG. 6 is a detailed view in section of the sleeve valves of FIG. 4.

Referring now to the drawing in which identical numerals will be employed to designate identical parts, numeral 11 designates a well bore drilled from the earth's surface to penetrate a plurality of subsurface earth formations which may contain hydrocarbons such as oil and/or gas. Arranged in the well bore 11 is a first pipe string 12 and a second pipe string 13 which are fluidly interconnected by a fluid interconnecting means 14 forming a passageway 15 between the pipe strings 12 and 13.

The lower end of the first pipe string 12 which may be the longer of the pipe strings is provided with a cement shoe 16 which includes a ball valve 17 seatable against a surface 18. The cement shoe has passageways 19 for passage of cement outwardly therefrom into the annulus 20 of the well 11.

The second pipe string 13 which may be shorter than the first pipe string 12 is provided with a wireline retrievable check valve 21 in which a ball valve member 22 is arranged and is seatable on a seating surface 23. The ball valve member 22 is held in place by a ported plate or spider 24. As will be noted, the upper end of valve 21 is provided with a fishing neck 25 whereby it may be engaged by a suitable grab tool attached to a wireline for moving the check valve 21 through the pipe string 13. It will be noted that the check valve 21 is provided with sealing means 26 and 27 for sealing with the wall of the pipe string 13.

The pipe string 13 is provided with a second check valve 28 which may be attached exteriorly to the pipe string 13 and communicate therewith by means of the port 29. The check valve 28 is provided with a valve member 30 seatable on a surface 31 and which is held in place by a spider or perforated plate 32. While the valve 28 is shown for convenience located exteriorly on the pipe string 13 and connected thereto, it may suitably be inserted in a mandrel fluidly communicating with the interior of the pipe string 13 and seatable therein by lowering through the pipe string 13.

In practicing the present invention, cement is flowed down through the pipe string 12 and is followed by a plug 33 which is seated in the bore 34 of the valve seat 18 and closes same indicating that the body of cement 35 has risen to the level 36 below the check valve 28. This is determined by a rise in pressure by closing of the port 34 by the plug 33.

It is undesirable to attempt to cement higher than the level 36 in that excessive pressures may be required to increase the level beyond the point 36.

In the practice of the present invention, cement is arranged in the annulus 20 above the level 36 by moving the check valve 21 to a point above the passageway 15 such that it is sealed above the passageway 15 and prevents flow down the pipe string 13 from preceding into the pipe string 12, the check valve 21 allowing only unidirectional flow from pipe string 12 to pipe string 13. Cementitious material such as a body 37 is then flowed down the pipe string 13 followed by a fluid material 38 which may be any suitable displacing fluid such as salt water, fresh water, drilling mud, and the like, or may be a hydrocarbon in a liquid phase. This causes the cement to be forced out through the port 29 in the check valve 28 into the annulus 20 and to form a body of cement 37a above the level 36. Thereafter displacing fluid such as 38 may

be flowed down through the pipe string 12, as shown in FIG. 3, and through the fluid passageway 15 and upwardly through the check valve 21 moving the valve 22 off its seat and allowing the cement 37 remaining in the pipe string 13 to be displaced upwardly to the well head and for removal from the pipe string 13. By virtue of the weight of the column of cement 37a in the annulus 20 and by use of a lighter fluid 38 for displacement of the cement 37, the upper valve 30 remains seated on the seating surface 31, and when the cement 37a has set, it is permanently closed.

It may thus be seen that with the employment of the method and apparatus of the present invention, it is possible to cement a plurality of pipe strings in a well without resorting to special tools for drillout and removing excess cement from the pipe string. The present invention is therefore quite advantageous and useful in that the several pipe strings in a well bore are cemented in place without difficulty.

After the cement 37a has set, the check valve 21 may be removed from the interior of pipe string 13 by lowering a wireline provided with a grab tool for engaging with the fishing neck 25, and the check valve 21 is then removed from the pipe string 13.

Thereafter both the pipe string 12 and the pipe string 13 may be perforated in vertically spaced-apart hydrocarbon productive zones. In order to perforate the pipe string 13, it may be necessary to employ a suitable orienting device such as one described in the patent to Bielstein, U.S. 2,781,098.

Referring now to FIG. 4, there are arranged in a well bore 40 a plurality of pipe strings 41, 42, 43, and 44. Pipe string 41 is fluidly connected by a suitable connecting means 45 to pipe string 42 to provide a fluid passageway 46. Pipe string 42 is connected by a suitable connecting means 47 to pipe string 43 to provide a fluid passageway 48. Pipe strings 43 and 41 are fluidly connected by a connecting means 49 providing a fluid passageway 50, and pipe strings 44 and 41 are fluidly connected by a connecting means 51 providing a fluid passageway 52.

The pipe string 41 may be the same length as the pipe strings 42, 43, and 44 or may be of greater length, and the lower end thereof is provided with a cement shoe 53 which is similar to cement shoe 16 and includes a ball valve 54 seatable against a surface 55. The cement shoe has passageway 56 for passage of cement out into the annulus 57 of the well 40.

In practicing the present invention, a valve 58, which is similar to the valve 21, is provided with a fishing neck 59 for engagement by a grab tool on a wireline, not shown, is placed in the pipe string 42 and sealed therein above the passageway 46 by sealing means 60 and 61. The valve 58 is provided with a ball 62 on a surface 63, the ball 62 being held in place by a suitable spider 64.

Arranged to communicate fluidly with a port 65 is a second valve 66 provided with a ball 67 seatable on a surface 68. The ball valve 67 is retained by the perforated plate 69 which allows fluid to pass out into the annulus 57.

The pipe strings 43 and 44 are similarly equipped with valves 66a and 66b which have ports identical to valve 66. Likewise, pipe string 43 is provided with sleeve valve 58a, which is similar to valve 58, and a second sleeve valve 58b, which is also similar to sleeve valve 58. Valve 58a, while similar to valve 58, is so designated that flow in either direction is possible as will be apparent from the mode of operation and from FIG. 4, where a sleeve assembly is shown. Pipe string 44 is provided with a sleeve valve 58c which is similar to valves 58, 58a, and 58b. It is to be noted that valve 58a is positioned to close off the passageway 48 while the valve 58b is arranged above the passageway 50, and the valve 58c is arranged above the passageway 52.

Valves 58b and 58c may or may not contain check

valves therein, such as valves 21 and 58, or may be constructed like valve 58a. When used as shown in FIG. 4 for controlling flow through passageways 50 and 52, a check valve may be desirable.

It is to be pointed out that passageway 47 and valve 58a are not necessary to the practice of the present invention but are shown to illustrate that auxiliary passageways may be provided between any two of the several strings provided sleeve valves like valve 58a are used therewith as illustrated.

Before describing the operation relative to FIG. 4 it is pointed out that valve 58 is lowered and positioned as shown in pipe string 42, and valve 58c is lowered and positioned in pipe string 44 above passageway 52. Valve 58b is lowered through pipe string 43 and positioned above passageway 50, and thereafter valve 58a is lowered through pipe string 43 and positioned opposite passageway 48. Thus, valve 58 closes communication downwardly through pipe string 42 but allows communication from pipe string 41 to pipe string 42. Valve 58a closes flow through passageway 48, while valves 58b and 58c allow flow unidirectionally from pipe string 41 to pipe strings 43 and 44, respectively.

In practicing the present invention with the apparatus and mode of FIG. 4, cement is pumped down through the pipe string 41 and out through the passageway 56 to a level generally designated by the numeral 70 with the plug 80 seating in the opening 81 of the cement shoe 53 to close same. When it is desired to cement to the level indicated by the numeral 71, cement is then flowed down through the pipe string 42 and out through the valve 66 until it reaches a level generally designated by the numeral 71. Thereafter, excess fluid cement is then reversed out the pipe string 42 in a similar manner to that described with respect to the excess fluid cement in pipe string 13, as described relative to FIG. 2.

When it is desired to cement to a still higher level, generally indicated by the numeral 72, cement is flowed downwardly through the pipe string 44 and out through the valve 66b to the level 72 as has been indicated, following which excess fluid cement in the pipe string 44 is reversed outwardly by flowing a suitable displacement fluid down through the pipe string 41 and through passage 52 and then upwardly in pipe string 44. Likewise, when it is desired to cement to a higher level, which may be to the wellhead, cement is flowed downwardly through the pipe string 43, the valve 58a being so constructed as to allow flow downwardly therethrough as described hereinbefore, and the valve 58b being constructed to allow flow upwardly but to prevent flow downwardly with the cement preceding out through the valve 66a to the top of the well or to a point intermediate the point 72 and the top of the well. Thereafter, excess fluid cement is circulated out from the pipe string 43 by flowing fluid downwardly through pipe string 41 through the passageway 50 and upwardly through the valve 58b and valve 58a.

It is to be pointed out that sleeve valves such as 58a may be used in lieu of the valves 21, 58, 58b, and 58c provided that suitable valving at the well head are provided and manipulated (opened or closed) to prevent movement of cement through the fluid communication between the pipe strings. Thus, if the well head valve is closed (as long as the casing is pressure-tight) there can be no flow into a particular pipe string. Valves 21, 58, 58b, and 58c are desirable and preferable, however, in the event pipe string pressure is not held.

The operation of the valves 21, 58, 58b, and 58c, as well as the sleeve valve 58a, will be understood more clearly by reference to the description of FIGS. 5 and 6 where similar numerals will designate identical parts.

Referring now to FIGS. 5 and 6, the valve 21 or 58 has a body member generally designated by numeral 90, and is provided on its upper end with slip segments 91 provided with a shoulder or fishing neck 92, the segments

91 being held in place by an annular member 93 attached by means 94.

The ball valve member 22 or 62 is designated to seat on a surface 95 when pressure is exerted thereon and is mildly urged away from the seating surface 95 by a weak spring 96, the lower end of which rests on a spider or ported plate 97. Spring 96 is of sufficient strength to prevent ball valve member 22 or 62 from seating and closing the valve 21 or 58 except when pressure from above is exerted thereon. Stating this otherwise, ball valve member 22 or 62 is not of sufficient weight to overcome the spring 96. Thus, the spring 96 is of selected and controlled strength such that spring 96 is of sufficient strength to raise the ball valve member 22 or 62 off the seating surface 95 such that when the valve 21 or 58 is raised, fluid is allowed to flow through the valve 21 or 58 on upward movement. Otherwise, swabbing of the well would occur since without the spring 96, the valve 21 or 58 would be fluid locked. Other means as desired such as a magnified prong on the pulling tool may be used in lieu of the spring when the valve 21 or 58 is raised.

The device of FIG. 6 is identical to that of FIG. 5 and the parts thereof are designated by identical numerals as applied to FIG. 5 excepting that the spider 24 or 64 is replaced by a spacing ring 105 and the check valve 22 or 62 and the spring 96 and spider 97 are omitted. In FIG. 6, the seals 26 or 60, and 27 or 61 are designated as 26a and 27a.

In positioning and setting the devices of FIGS. 5 or 6, these devices are lowered on a wireline to position the device properly. The slip segments 91 are then set by jarring downwardly on the slip segments 91 by exerting force against the shoulder 92, which causes the surface 102 to move downwardly on the surface 101.

Although slips may be provided on the lower end of valve 21 or 58, difficulties may be encountered because of inadvertent setting of such slips while going into the hole. In that there is no need for preventing downward movement of the device in excess of the moderate downward holding power afforded by friction from slips 91, ordinarily there is no need for slips on the lower end of the tool.

In moving the devices of FIGS. 5 and 6, an upward pull is taken on the fishing neck 92 which causes the slip segments 91 to move upwardly on the surface 101 allowing the tool or device to be removed from the pipe string, or moved and set at a different location, as may be desired.

By this mode of operation, a plurality of pipe strings, which may be three or four or a greater number, may be cemented in a well bore.

The present invention is of great utility in that for the first time it is possible to cement a plurality of side-by-side parallel pipe strings in a well bore without resorting to expensive drilling operations and the use of special tools.

While the invention has been described and illustrated by reference to dual and quadruple pipe string completions, the invention is applicable to triple completions employing three pipe strings. Likewise, a greater number of pipe strings than four may be used provided the principles and mode described herein are employed.

The nature and objects of the present invention having been completely described and illustrated, what I wish to claim as new and useful and secure by Letters Patent is:

1. A method for cementing a plurality of side-by-side parallel pipe strings fluidly interconnected in a well bore, one of said pipe strings having a greater length than another of said pipe strings, and said pipe string of greater length allowing passage of fluid out its lower end and said another pipe string allowing passage of fluid through its wall at a selected point, which comprises sequentially closing fluid communication between said pipe strings, flowing a cementitious material down said one pipe string and out the end thereof to fill the annulus between the pipe strings and the wall of said well bore to a predetermined level below the selected point, opening communi-

cation for flow unidirectionally from the one to the another pipe string, flowing cementitious material down said another of said pipe strings and into the annulus above said first flowed cementitious material, and then flowing a displacing fluid down said one pipe string and displacing cementitious material from said another pipe string whereby said pipe strings are cemented in said well bore.

2. A method for cementing two side-by-side parallel pipe strings fluidly interconnected in a well bore, the first of said pipe strings allowing passage of fluid out its lower end and the second of said pipe strings allowing passage of fluid through its wall at a selected point, which comprises sequentially closing fluid communication between said pipe strings, flowing a cementitious material down said first pipe string and out the end thereof to fill the annulus between the pipe strings and the wall of said well bore to a predetermined level below the selected point, opening communication for flow from the first to the second pipe string, flowing cementitious material down said second pipe string and into the annulus above said first flowed cementitious material, and then flowing a displacing fluid down said first pipe string and displacing cementitious material from said second pipe string whereby said pipe strings are cemented in said well bore.

3. A method for cementing a plurality of side-by-side parallel pipe strings in a well bore, one of said pipe strings allowing passage of fluid out its lower end and the other of said pipe strings allowing passage of fluid through its wall at a selected point, said pipe strings fluidly communicating with each other, which comprises sequentially closing fluid communication between said pipe strings, flowing a cementitious material down said one pipe string and out the end thereof to fill the annulus between the pipe strings and the wall of said well bore to a predetermined level below the selected point, restoring communication for flow from the one to the other of said pipe strings, flowing cementitious material down said other of said pipe strings and into the annulus above said first flowed cementitious material, and then flowing a displacing fluid down said one pipe string and displacing cementitious material from said other pipe string whereby said pipe strings are cemented in said well bore.

4. A method for cementing a plurality of side-by-side parallel pipe strings fluidly interconnected in a well bore, one of said pipe strings allowing passage of fluid out its lower end and the other of said pipe strings allowing passage of fluid through its wall at a selected point, which comprises sequentially lowering a check valve into said other pipe string and positioning it to block fluid communication between said pipe strings, flowing a cementitious material down said one pipe string and out the end thereof to fill the annulus between the pipe strings and the wall of said well bore to a predetermined level below the selected point, raising said check valve in said other pipe string to position it to open communication for flow unidirectionally from the one to the other of said pipe strings, flowing cementitious material down said other of said pipe strings and into the annulus above said first flowed cementitious material, then flowing a displacing fluid down said one pipe string and displacing cementitious material from said other pipe string whereby said pipe strings are cemented in said well bore, and then removing said check valve.

5. A method in accordance with claim 4 in which the check valve is lowered, raised, and removed on a wireline.

6. Apparatus for use in a well which comprises a plurality of side-by-side pipe strings arranged in said well, fluid interconnection means interconnecting said pipe strings in said well, a cement shoe on the lower end of one of said pipe strings, a retrievable first check valve arranged in a first position in another of said pipe strings to block said fluid interconnection means and movable to a second position to open said fluid interconnection means, said first check valve allowing fluid flow upwardly in said

another pipe string, and a second check valve connected to said another pipe string above said fluid interconnection means, said second check valve allowing fluid flow into the annulus between said pipe strings and the wall of said well.

7. Apparatus in accordance with claim 6 in which the second check valve is arranged on the exterior of said another pipe string.

8. A method for cementing a plurality of side-by-side parallel pipe strings fluidly interconnected in a well bore, one of said pipe strings allowing passage of fluid out its lower end and another pipe string allowing passage of fluid through its wall at a selected point, which comprises sequentially closing fluid communication between said pipe strings, flowing a cementitious material down said one pipe string and out the end thereof to fill the annulus between the pipe strings and the wall of said well bore to a prede-

termined level below the selected point, opening communication for flow from the one to the another pipe string, flowing cementitious material down said another of said pipe strings and into the annulus above said first flowed cementitious material, and then flowing a displacing fluid down said one pipe string and displacing cementitious material from said another pipe string whereby said pipe strings are cemented in said well bore.

9. A method in accordance with claim 3 in which the selected point is above the fluid communication.
